REFRIGERATOR EVAPORATOR AND SHELF
LAY-OUT

Ray A. Sandberg, Waukegan, Ill., assignor, by
mesne assignments, to Houdaille-Hershey Cor-
poration, Detroit, Mich., a corporation of Mich-
igan

Application November 1, 1934, Serial No. 750,940

5 Claims. (Cl. 62—126)

This invention relates to a refrigerator evaporator unit which itself serves as an extended shelf or support for ice trays.

More specifically, this invention relates to a stamped sheet metal evaporator unit adapted to be readily mounted in horizontal position near the top of a refrigerator cabinet to cool the same and also form a support for ice trays and the like.

10 Evaporator units heretofore known have been shaped to define an enclosed sharp freezing chamber or inclosure. This type of construction requires bending operations and the use of added shelf supports and the like for ice trays. Furthermore, the ice trays thus mounted in the sharp freezing chamber, with the exception, usually of only the lowermost tray, do not have intimate thermal contact with the evaporator unit.

15 The present invention provides a generally flat evaporator unit which may be horizontally mounted in a refrigerator cabinet to cool the same and form a supporting shelf for ice trays. According to this invention, the ice trays are not superimposed upon each other, but are each in intimate and extensive thermal contact with a wall of the evaporator unit itself.

20 It is therefore an object of this invention to form a simple and inexpensive evaporator unit for refrigerator cabinets that is capable of efficiently absorbing heat from the cabinet and from trays of liquids to be frozen.

25 A further object of this invention is to provide a flat sheet metal evaporator unit and shelf that is adapted to be readily mounted in a refrigerator cabinet.

30 A further object of this invention is to provide a refrigerant expansion chamber having a plurality of expansion ducts formed by stamped de-
pressions in the walls of the unit, with some of said depressions defining compartments for ice trays.

35 Another object of this invention is to provide a flat stamped sheet metal evaporator unit which also forms a support for ice trays and for a moisture collecting tray.

40 Other and further objects of this invention will be apparent from the following specification and drawings which form a part of this specification.

45 On the drawings:

Figure 1 is a fragmentary front elevational view illustrating the manner in which an evaporator unit of this invention is mounted in a refrigerator cabinet.

Figure 2 is a top plan view of an evaporator unit according to this invention, illustrating the integral ears or lugs for supporting the unit before the lugs are bent downwardly.

Figure 3 is a bottom plan view of an evaporator unit according to this invention.

Figure 4 is an enlarged cross-sectional view taken substantially along the line IV—IV of Figure 2.

Figure 5 is an enlarged cross-sectional view taken substantially along the line V—V of Figure 2.

Figure 6 is a view taken substantially along the line VI—VI of Figure 1 illustrating the manner in which the evaporator unit is attached to a refrigerator cabinet.

Figure 7 is an enlarged cross-sectional view taken substantially along the line VII—VII of Figure 3.

Figure 8 is a cross-sectional view taken substantially along the line VIII—VIII of Figure 7.

As shown on the drawings:

In Figures 1 and 6, the reference numeral 10 indicates generally a refrigerator cabinet of a conventional type having an inside top wall 11 and side walls 12 and 13. An evaporator unit 20, according to this invention, is mounted in the cabinet 10 on the side walls 12 and 13, as will be more fully hereinafter described. A front enclosure plate 14 is positioned in front of the evaporator unit. The plate 14 is preferably suspended from the top 11 of the cabinet and is in spaced relation from the front of the evaporator unit 20. The plate 14 is provided with a plurality of apertures 15, 16, and 17, which are adapted to receive ice trays 18 therethrough. The ice trays 18 rest on the evaporator unit 20 in compartments provided therefor, as will be hereinafter described. Manually operable devices 19 may conveniently be mounted on the enclosure plate 14 for regulating or controlling refrigerating conditions within the refrigerator cabinet.

As best illustrated in Figures 2 to 5 inclusive, the evaporator unit 20 of this invention comprises a pair of stamped metal sheets 21 and 22 forming the top and bottom walls of the evaporator, respectively, and together providing a generally flat shelf.

The sheets 21 and 22 are formed from rectangular flat metal sheets or plates. The sheet 21 is larger than the sheet 22 and has portions cut from the sides thereof, so that laterally extending ears or lugs 23 are provided at the corners of the plate. The ears 23 are bifurcated

at their ends to provide spaced fingers 24, as shown in Figure 2. These fingers are bent downwardly and serve to mount the finished evaporator unit in a refrigerator cabinet, as will be hereinafter described.

The sheet 21 is stamped to provide a semi-cylindrical header portion 25 and a plurality of spaced beads 26 in parallel relation. A bead 27 is also formed at the rear end of the beads 26 at right angles to and connecting the header portion 25 and beads 26. The beads 26 and 27 define the stalls or compartments 28 for the ice trays 18, as shown in dotted lines in Figure 4.

The bottom wall 22 is stamped to form header depressions 29 and 30 near the ends of the shell. The header portions 29 and 30 are connected by a plurality of smaller stamped portions or beads 31 which serve as refrigerant expansion ducts. A feed duct 32 is stamped centrally of the sheet 20 to traverse and communicate with each of the passages 31.

The stamped and cut sheets are then prepared for a welding operation. For this purpose, the sheets are superimposed and thin welding shims 25 or sheets of welding metal (not shown) are preferably placed between the sheets, as is more fully described in my copending application entitled "Evaporator unit and process", Serial No. 736,183, filed July 20, 1934.

As shown in Figure 4, the stamped sheet or shell 21 is preferably formed with a peripheral flange 33, which is bent around the periphery of the shell 22 to hold the superimposed shells in assembled relation. The assembled unit is then placed in a welding furnace and welded according to the process disclosed in my above referred to application. It should be understood, however, that other welding methods may be used without departing from the scope of this invention.

After the welding operation, the two shells 21 and 22 are thoroughly fused together along all contacting surfaces, while the stamped portions in the shells form header ducts and refrigerant expansion chambers. As shown in Figure 4, the stamped portions 25 and 29 register with each other to form a tubular header 34. The stamped depression 30 forms a semi-cylindrical header 35 at the opposite side of the unit, connected to said header 35 by the ducts provided by the bead 27 in the upper wall and the beads 31 in the lower wall.

The laterally extending ears 23 of the shell 21 are next bent downwardly as shown in Figures 4 and 5. Each finger 24 of the ears 23 is turned inwardly at the end thereof to provide a flange 36 for a purpose to be hereinafter described.

The wall portion 25 of the sheet 21 is punctured at one end thereof as shown at 37 to provide an outlet for expanded refrigerant.

The end of the feed conduit 32 in the plate 22 is preferably formed as shown in Figures 7 and 8. In this construction, the plate 22 is stamped as at 51 to provide a receptacle for a strip of reinforcing metal 38 which is stamped into the passageway 32 to reinforce the same at the end thereof. The top plate 21 is preferably stamped as shown at 39 to form an arcuate wall portion for the passageway 32 so that the same may be readily joined with the refrigerant supply conduit 40. (Figures 2 and 3.) As shown in Figure 8, the passageway or duct 32 is enlarged at the end thereof so that the opening thus formed with the portion 39 may readily receive

a standard sized coupling 40 within the reinforcing strip 38.

Compressed refrigerant from the compressor is supplied to the evaporator unit through the conduit 40 and into the distributing duct 32. The refrigerant is allowed to expand through the expansion ducts 31 into the headers 29 and 30. As the refrigerant absorbs heat, it is vaporized, and the expanded vapors are withdrawn through the beads 26 and 27, which also act as passageways, into the header 34, from which it is removed through the opening 37 and returned to the compressor.

As shown in Figures 1 and 6, the evaporator unit is mounted in a refrigerating cabinet from the side walls 12 and 13 thereof and near the top 11 of the refrigerator. The unit is preferably spaced from the back 9 of the refrigerator cabinet as shown in Figure 6 to permit a free circulation of air in the cabinet. The side walls 12 and 13 of the cabinet 10 are provided with stud supports, such as bolts 41 and the like. The fingers 24 of the unit 20 are slipped over the bolts 41, and the unit is thus readily mounted in operative position.

As described above, the ends of the fingers 23 are turned in at 36. The turned-in portions 36 act as supports for a moisture collecting tray 42 (Figure 1). The tray 42 is readily slid under the unit 20 when the refrigerator is being defrosted. The tray is preferably removed after each defrosting operation.

As shown in Figure 6, the enclosure plate 14 is suspended from the top 11 of the cabinet 10 and is in spaced relation in front of the unit 20. The closure plate is provided with apertures 15, 16, and 17 (Figure 1) which permit the insertion of ice trays 18 into the stalls 8. The ice trays are therefore in intimate extended thermal contact with the upper wall of the evaporator unit, and ready freezing of ice cubes in each tray is thus ensured.

It should be understood that the arrangement of header and expansion ducts may be greatly varied without departing from the scope of this invention, since it is obvious that other arrangements for the circulation of refrigerant in the unit may be used.

The invention, therefore, provides a flat evaporator unit for refrigerators that is simple in design, efficient in operation, and cheap. The necessity for occupying large spaces in a refrigerator cabinet for the evaporator unit is avoided, since the unit of this invention does not in any way obstruct more than a small part of the top of the cabinet. The food storage space is thus greatly increased without increasing the size of the cabinet.

I am aware that many changes may be made and numerous details of construction varied through a wide range without departing from the principles of this invention, and I, therefore, do not purpose limiting the patent granted hereon otherwise than necessitated by the prior art.

I claim as my invention:

- An evaporator unit for refrigerators comprising complementary registering sheet metal shells joined together in a single plane to form a generally flat shelf for supporting a plurality of ice trays directly thereon and providing header and interconnecting expansion ducts for refrigerant flow therebetween, said shells being welded together along inner contacting surfaces and one of said shells having integral downwardly projecting ears at the corners

thereof, said ears having stud-receiving openings therein for securing the unit in a horizontal position to the side walls of a refrigerator.

2. An evaporator unit and moisture collecting tray assembly comprising stamped sheet metal shells joined together in a single plane to define therebetween expansion ducts for refrigerant flow and a shelf for supporting ice trays directly thereon, downwardly depending stud engaging fingers at the corners of said shells for mounting the unit, said fingers being flanged at the ends thereof, and a tray slidable therein for collecting moisture when the unit is defrosted.

3. An evaporator unit comprising flat rectangular metal plates having offset portions stamped therein to define tubular headers and communicating passageways between the plates, said plates being welded together in a single plane along all inner contacting surfaces, and having bifurcated fingers extending therefrom at the sides thereof for mounting the unit in a cabinet.

4. A refrigerant cabinet comprising a box having top, rear and side walls, studs projecting from the side walls spaced from the top wall, and an evaporator unit lying in a single horizontal plane in said box and having dependent apertured ear portions engaging said studs to support the unit entirely from the side walls of the box in spaced relation from the top wall.

5. A refrigerator cabinet comprising a box having top, rear and side walls, studs projecting from the side walls in spaced relation from the top wall, an evaporator unit lying in a single horizontal plane in said box and having downwardly depending bifurcated ear portions at the corners thereof engaging said studs to support the unit from the side walls of the box in spaced relation from the top wall, said ear portions having inturned flanges formed thereon and a tray slidable on said flanges for collecting moisture from the evaporator unit.
